HANGER FOR DISPLAY PACKAGE

Naoyuki Iso, 3 of 27 Oimatsu-cho,
Nishinomiya, Hyogo, Japan

Filed Dec. 1, 1971, Ser. No. 203,939

Term of patent 14 years

Int. Cl. D6—08

U.S. Cl. D6—252

FIG.1

FIG.5

FIG. 1 is a face view of a hanger for display package, showing my design;

FIG. 2 is a side view looking at FIG. 1 from right to left;

FIG. 3 is a side view looking at FIG. 1 from left to right;

FIG. 4 is a top view looking down upon FIG. 1; and

FIG. 5 is a bottom view looking up at FIG. 1.

I claim:

The ornamental design for a hanger for display package, as shown.
